UNITED STATES PATENT OFFICE

EDMUND JOSEPH KANE, OF CHICAGO, ILLINOIS

EXCAVATING MACHINE

Application filed March 9, 1928. Serial No. 260,365.

This invention relates to improvements in machines of the excavating type and in the present embodiment is shown applied to a machine of the character employing material handling buckets of the clam shell type. More specifically, the invention relates to a novel and efficient combination of elements for manually controlling the operation of an internal combustion engine associated with the machine while the material handling devices are being manipulated.

One object of the present invention is to provide a novel construction and arrangement whereby the operation of a governor controlled internal combustion engine associated with excavating machines may be readily varied at the will of the operator.

Another object of the invention is to provide manually actuated means for yieldingly resisting the operation of engine governor mechanism for controlling the operation of an excavating machine engine.

A further object of the invention is to provide a novel construction and arrangement of elements for controlling the operation of a governor controlled excavating machine engine, and which may be manually and readily actuated by means conveniently mounted on the operating lever of such machines for controlling the operation of the material handling device.

A still further object of the invention is to improve devices of this character in sundry details hereinafter described and particularly pointed out in the appended claims.

One embodiment of the invention is shown for illustrative purposes in the accompanying drawings, in which

Fig. 1 is a side elevation of an excavating machine illustrating an embodiment of my invention applied thereto.

Fig. 2 is a plan view of a portion of the excavating machine shown in Fig. 1 illustrating the arrangement of elements comprising features of my invention.

Fig. 3 is a fragmentary elevational view of a portion of a carburetor, governor mechanism and means for controlling the operation of said governor mechanism.

Fig. 4 is an enlarged fragmentary eleva-

tional view taken as indicated by the line 4-4 of Fig. 2.

Figs. 5, 6 and 7 are plan, side and end views, respectively, of a mechanism forming a part of my invention.

Referring to the drawings, the illustrative embodiment of the invention is shown in connection with an excavating machine having a transporting truck 10 provided with traction wheels 10a, and on which is pivotally mounted a swing body or frame 11.

Suitably mounted on the frame 11 is a boom 12 adapted to be raised and lowered to various angular positions with respect to the frame 11, and to the outer end of which is suspended a material handling device or bucket 13 of a design well known to persons familiar with machines of this character as of the clam shell type. Suitably connected to the bucket 13 is a cable 14 adapted to pass upwardly and over a sheave 15 at the upper end of the boom 12 and thence downwardly around a rotatable cable drum 16, (Figs. 1 and 2) mounted on the frame 11, in a manner to be wound on or unwound from the drum for the purpose of raising and lowering the bucket, the cable 14 being suitably trained over a combination of sheaves 17 and operating in conjunction with a plurality of lever arms 18 mounted on the bucket in a manner to close the pivoted portions or jaws of the bucket when in position to grasp or engage the material to be handled. The drum 16 is adapted to be driven by a suitable gear train consisting of a gear 19, pinion 20 and shaft 21, to the outer end of which is secured a pulley 22, over which is trained a belt 23 operatively related to a pulley 24 mounted on the crank shaft 25 of an internal combustion engine 26 suitably mounted on the frame or swing body 11.

For operatively connecting the gear train and engine 26, above described, to the drum 16, suitable clutch mechanism 27 may be employed, the shiftable member of which may be moved into and out of clutch actuating position by means of a forked arm or clutch shipper lever 28 secured to a rock shaft 28a rotatably mounted in bearings 29, the said shaft 28a being connected by means of an arm 30 and link 31 to an arm 32 secured

95

to one end of a rock shaft 33 pivotally mounted in suitable bearings 34 on the frame 11. Secured to the rock shaft 33 and positioned conveniently to the hand of the operator is 5 an operating lever 35 by which the clutch mechanism may be actuated in a manner to connect the engine 26 with the drum 16 for closing and hoisting the bucket 13.

A cable 36 is connected to the bucket 13 and 10 trained around the sheave 15 and a drum 37, Figs. 1 and 2, which has suitable mechanism associated therewith, and common to this type of excavating machine, for opening the pivoted portions or jaws of the bucket 13 15 when it is desired to deposit the material carried thereby.

In excavating machines of the character described, employing power units or engines of the internal combustion type, it is common 20 practice to operate such engines under the control of governor mechanism, which in effect, produces what might be termed a constant speed engine, or in other words, an engine having a fixed maximum speed, and 25 which, due to some kinds of work that the engine and machine are called upon to perform, is not very high. It has been found in the use of such machines that certain work 30 may be speeded up if it were not for the fact that the maximum speed of the engine was absolutely under the control of the governor. This would be true, for example, when the machine was working in loose 35 ground, such as sand or gravel, in which cases it may for example be found desirable to speed up the closing of the jaws of the bucket and thereby increase the efficiency of the machine, or if found desirable, the hoisting of the bucket might also be accelerated.

One of the objects of my invention is to obtain this acceleration readily and conveniently, if desired, by a novel construction and arrangement which will now be described.

40 In the illustrative embodiment shown in the drawings, the type of engine employed is provided with a carburetor, diagrammatically shown at 38 in Fig. 3, which is connected by means of a tube 39 to an intake manifold 40 by which the fuel is conducted to the combustion chambers of the engine in the usual way, and pivotally mounted in the tube 39 is a shaft 41 to which is connected a throttle valve 42 adapted to be positioned at various angles with respect to the passage or opening in the tube 39, in a manner to control the amount of fuel passing therethrough to the combustion chambers.

Secured to the end of the shaft 41 outside the tube 39 is an arm 43, the upper or free end of which is pivotally connected to one end of a link 44, the opposite end of which is pivotally connected to the upper end of an arm 45 secured at its lower end to a rock shaft 46 adapted to oscillate

in bearings formed in the cup-like stationary portion 47 of governor mechanism 48, shown in the present instance as of the fly ball type and which comprises a collar 49 secured to the upper end of a governor shaft 50, the 70 said shaft being suitably connected to the cam shaft or other moving part of the engine in a manner to be driven thereby. A sleeve 51 is loosely mounted on the shaft 50 in a manner to be moved longitudinally thereof and driven thereby by means of an elongated transversely extending tongue and groove connection 52 formed on the collar 49 and sleeve 51, respectively. Secured to opposite sides of the sleeve 51 and extending radially 80 and upwardly thereof are a plurality of arms 53 to the upper ends of which are pivotally connected fly ball arms 54 having horizontally disposed inwardly extending portions 55 adapted to be engaged by an annular groove 85 56 formed in the collar 49, the lower extremities of the arms 54 being connected by means of tension springs 57. The lower end of the sleeve 51 is provided with an annular flange 58 adapted to underlie and engage the inner 90 or adjacent free end of a short arm 59 secured to the shaft 46 within the cup-like stationary portion 47.

It will be observed from the foregoing description that the rotation of this governor 95 shaft 50 will carry with it the collar 49, sleeve 51 and governor ball arms 54, and that as the engine approaches its predetermined maximum speed, the fly balls will be thrown outwardly and the sleeve 51 lifted in a manner 100 to cause the flange 58 to lift the arm 59, thereby rocking the shaft 46 in its bearings, and through its connection with the throttle valve 42 by means of the arm 45, link 44 and arm 43 will cause the valve 42 to be positioned 105 at various angles with respect to the passage through the tube 39, thereby controlling the passage of fuel therethrough to the combustion chambers. It will be observed also that an engine controlled by a governor as above 110 described is limited to a predetermined maximum speed, depending upon the adjustment of the governor.

In order to control the operation of the governor and thereby, when desired, to accelerate the speed of the engine, a rocker arm 60 is pivotally mounted at 61 intermediate its ends, preferably on the frame of the engine 26, and connected to the upper end of the arm 60 and to the upper end of the arm 45 is a resilient member or spring 62 adapted to yield in a manner to permit of the normal operation of the governor and engine under 115 normal conditions. Pivotally connected to the lower end of the rocker arm 60 is one end of a short link 63, the opposite end of which is pivotally connected to one arm of a bell crank lever 64 mounted to oscillate on a bracket 65 secured to the swing body or frame 120 11. To the other arm of the bell crank lever 130

64 is pivotally connected a relatively long link or rod 66 extending forwardly of the frame 11 to a point substantially adjacent the forward edge thereof, and at its forward 5 end is provided with an upturned portion 67 adapted to be pivotally connected to one arm of a bell crank lever 68, (see Figs. 2, 5, 6 and 7) pivotally mounted on a bracket 69 secured to the swing body or frame 11 adjacent the rock shaft 33. The other arm of 10 the bell crank lever 68 is provided with a forked portion 70, the arms of which extend on opposite sides of the rock shaft 33 and have their outer or free ends provided with 15 notches 71 adapted to engage studs or trunnions 72 secured to or carried by a ring 73 rotatably positioned in an annular groove 74 formed in a sleeve 75 loosely mounted on the rock shaft 33 in a manner to be moved longitudinally thereof. Formed also in the 20 sleeve 75 and spaced longitudinally thereof from the groove 74 is a second annular groove 76 adapted to receive therein a relatively rotatable ring 77 having oppositely disposed 25 radially extending studs or trunnions 78 formed thereon and adapted to be engaged by forked arms 79 of a lever 80 pivotally mounted by means of a pin 81 to the operating lever 35 secured to the rock shaft 33. 30 Pivots connected to the lever 80 intermediate its end portions is one end of a link 82, the opposite end of which is pivotally connected to a hand lever or member 83 pivotally mounted on the operating lever 35 35 adjacent the upper end thereof.

It will be observed from the foregoing description and by reference particularly to Figs. 5, 6 and 7 that the operating lever 35 and rock shaft 33 may be oscillated in the 40 bearings 34 to actuate the clutch mechanism 27 for connecting the engine or power unit 26 with the cable drums 16 and 37 in a manner to wind the cables 14 and 36, respectively, thereon, the drum 37 being frictionally 45 operated by drum 16 in a manner old and well known in the art and not shown, thereby closing the pivoted portions of the clam shell bucket 13 to engage the material to be handled and hoist the same by a continued 50 rotation of the drums, for the purpose of depositing it in any manner desired. It will be observed also that this manipulation of the operating lever 35, by reason of the construction shown in Figs. 5 to 7 inclusive, 55 does not in any way change the normal position of the bell crank levers 68 and 64, and their associated connections, or in any way effect the normal operation of the governor mechanism 48 and engine 26. As heretofore mentioned, it has been found desirable at 60 times, when operating the bucket in loose material such as sand, gravel or the like, to speed up or accelerate the closing and possibly the hoisting of the bucket, and in this connection it will be observed further 65 that by manipulating the hand lever or member 83, conveniently mounted adjacent the upper end of the operating lever 35 by which the clutch mechanism 27 is actuated, the lever 80 will be rocked about the pin 81 in a manner to move the sleeve 75, together with the ring 73, longitudinally of the shaft 33, thereby rocking the bell crank lever 68 on the bracket 69 and exerting a pull on the rod 66. This movement of the rod will shift the bell 70 crank lever 64 to exert an endwise thrust on the link 63 in a manner to move the rocker arm 60 about its pivotal support 61 and cause the additional tensioning of the resilient member or spring 62 connected to the upper 75 end of the lever 45. It will be observed from the foregoing description that the manipulation of the hand lever 83 increases the tension of the spring 62 in a manner to resist the normal operation of the governor 80 mechanism, thereby holding the throttle valve 42 open and permitting the engine to attain a greater speed than is possible under normal conditions, before the effect of the governor mechanism on the sleeve 51, short 85 arm 59 and arm 45 is sufficient to overcome the increased tension of the spring 62, thereby speeding up or accelerating the rotation of the drums 16 and 37 around which the cables 14 and 36 are trained, and in this 90 manner effecting a more rapid closing operation of the bucket, and if desired, the hoisting thereof.

Obviously, connections may be made through suitable gearing between the engine and traction wheels 10a of the truck 10 for the purpose of moving the machine, and also with suitable driving mechanism mounted on the swing body or frame 11 for the purpose of swinging the frame about its pivotal connection with the truck, and, in as much as the hand lever or member 83 is located conveniently to the hand of the operator, it will be obvious also that, if desired, the movement of the machine from place to place and the swinging movement of the frame on the truck 10 may be speeded up or accelerated by the manipulation of the hand lever 83, as above described with reference to the manipulation or handling of the bucket 13.

Obviously, the present invention is not limited to the precise construction and arrangement shown and described, as the same may be variously modified without departing from the spirit and scope of the invention as set forth in the appended claims.

What I claim as my invention and desire to secure by Letters Patent is:

1. In an excavating machine, the combination with a power unit consisting of a governor controlled internal combustion engine provided with a throttle control valve for controlling the power and speed of the engine, an operating hand lever for controlling one of the operating functions of the exca-

vating machine, of a hand operated device operatively connected with and carried by said hand lever, and a resilient operating connection between said hand operated device, said governor control mechanism and said throttle for moving said throttle irrespectively of the position or movement of said hand lever for accelerating the speed of said power unit, said resilient member being adapted to yield and restore the normal functioning of the governor controlling means when the latter passes a predetermined excessive speed.

2. In an excavating machine, the combination with an internal combustion engine having a throttle valve associated therewith, a centrifugally operated governor device operably connected with the engine, a shiftable hand lever for controlling one of the operating functions of the excavating machine, a supplemental lever mounted on said operating lever, a lever pivotally mounted adjacent said centrifugal governor mechanism and adapted to be operated in one direction of its movement by said governor mechanism, an operating connection between the last said lever and said throttle valve, and a resilient connection between said lever operated by the governor and the supplemental lever carried by the operating lever on the frame, whereby the normal functioning of the governor mechanism will be resumed by overcoming the resistance of the resilient connection to prevent dangerous or excessive speed.

3. In a power operated machine having a power generating unit comprising a governor controlled internal combustion engine including a throttle, the combination with a plurality of separate mechanisms adapted for selective operation by said power unit, each of said mechanisms including clutch devices for selectively connecting them with the power unit, of a plurality of pivoted control levers mounted on said machine adjacent each other for operating said respective clutch devices, said levers being arranged for the convenient use of an operator in a single station on said machine, supplemental movable means on one of said levers, and operative connections between the last said means and the said governor and throttle devices of said governor controlled internal combustion engine whereby through the movement of the means on said lever, the operator may accelerate the speed of the engine.

4. The combination in an excavating machine having a plurality of separately operable mechanisms adapted to perform the usual functions of such machines as excavating, travelling and swinging movements, said power unit consisting of a governor controlled internal combustion engine including a throttle adapted to be selectively connected with said mechanisms, a pivoted hand lever adapted to operatively connect and dis-

connect said power unit in relation to one of said devices, and means adapted to be manually operated carried by said pivoted lever and having operative connections with the said governor and throttle devices of said governor controlled internal combustion engine for accelerating the speed thereof. 70

5. The combination in an excavating machine having a plurality of separately operable mechanisms adapted to perform the usual functions of such machines as excavating, travelling and swinging movements a power unit, the said power unit consisting of a governor controlled internal combustion engine adapted to be selectively connected with said mechanisms, a pivoted hand lever adapted to operatively connect and disconnect said power unit with relation to one of said mechanisms, a supplemental lever carried by said pivoted lever, a shaft supporting said pivoted lever, a sleeve slidably mounted on said shaft, a shifter fork pivoted on said lever and engaging said sleeve, operative connections between said supplemental lever and said shifter fork, a second shifter fork pivotally supported adjacent said shaft with the bifurcated portion thereof engaging said sleeve, and operative connections between the last said shifter fork and the usual governor and throttle devices of said governor controlled internal combustion engine for accelerating the speed thereof. 80 85 90 95

6. The combination in an excavating machine having a plurality of separately operable mechanisms adapted to perform the usual functions of such machines as excavating, travelling and swinging movements a power unit, the said power unit consisting of a governor controlled internal combustion engine adapted to be selectively connected with said mechanisms, a pivoted hand lever adapted to operatively connect and disconnect said power unit with relation to one of said mechanisms, a supplemental lever carried by said pivoted lever, a shaft supporting said pivoted lever, a sleeve slidably mounted on said shaft, a shifter fork pivoted on said lever and engaging said sleeve, operative connections between said supplemental lever and said shifter fork, a second shifter fork pivotally supported adjacent said shaft with bifurcated portion thereof engaging said sleeve, and operative connections between the last said shifter fork and the usual governor and throttle devices of said governor controlled internal combustion engine, including a resilient connection with the governor mechanism for accelerating the speed of the engine and being adapted to render the governor mechanism inoperative to control the engine speed within predetermined limits above the speed normally limited by said governor, and permitting the governor to function to limit excessively dangerous speeds above said limits. 100 105 110 115 120 125 130

7. The combination in an excavating machine having a plurality of separately operable mechanisms adapted to perform the usual functions of such machines as excavating, travelling and swinging movements a power unit, said power unit consisting of a governor controlled internal combustion engine adapted to be selectively connected with said mechanisms, a pivoted hand lever adapted to operatively connect and disconnect said power unit in relation to one of said

mechanisms, means adapted to be manually operated, carried by said pivoted lever, and operative connections between said means and the usual governor and throttle devices of said governor controlled internal combustion engine, comprising a resilient member interposed between said supplemental lever and said governor mechanism and a substantially nonflexible operative connection between the governor and said throttle device. ⁷⁰ ⁷⁵
